R. S. Berry,
ATTORNEY.

UNITED STATES PATENT OFFICE.

CHARLES F. COLBY, OF LOS ANGELES, CALIFORNIA.

SHOE-BUCKLE HOLDER.

1,333,466.

Specification of Letters Patent.

Patented Mar. 9, 1920.

Application filed April 3, 1919. Serial No. 287,206.

To all whom it may concern:

Be it known that I, CHARLES F. COLBY, a citizen of the United States, residing at Los Angeles, in the county of Los Angeles and

5 State of California, have invented new and useful Improvements in Shoe-Buckle Holders, of which the following is a specification.

This invention relates to a buckle support 10 of the type adapted to be detachably engaged with the edge of a slipper and to afford a means for holding a buckle in place.

It is the object of this invention to provide a device for attaching a buckle to a slipper so constructed that the buckle will be securely held against displacement.

Another object is to provide means whereby the buckle support may be securely 20 affixed to the upper marginal edge of the slipper to project upwardly therefrom and whereby projections beneath or over the vamp of the slipper other than edge thereof will be obviated.

25 Other objects will appear hereinafter.

The invention is illustrated in the accompanying drawings in which:

Figure 1 is a perspective view of a slipper illustrating the invention as applied.

30 Fig. 2 is a perspective view of a back member for attachment to the slipper.

Fig. 3 is a perspective view of a separable plate adapted to form a connection between a buckle and the back plate shown in 35 Fig. 2.

Fig. 4 is a perspective view illustrating a buckle having a back bar with which the separable plate is engageable.

Fig. 5 is a detail in vertical section showing 40 the manner of mounting a buckle on my buckle support.

Fig. 6 is a detail showing a modified form of the connection between the back member and the slipper.

45 Fig. 7 is a detail of a modified form of a locking means.

More specifically, 7 indicates the back plate which is curved to substantially conform to the instep and is here shown as 50 approximately rectangular in shape and formed with inturned flanges 8 on its vertical edges and having narrow tangs 9 on its lower edge formed with perforations 10 to adapt it for being stitched to the marginal edge of a slipper. The back plate is preferably formed with a pair of the tangs

9 spaced apart and arranged adjacent the edges thereof below the flanges 8 and which tangs may be engaged with the edge of the slipper either on the under or outer sides 60 of the slipper edge. However, an intermediate flange 11 may be formed between the flanges 9 as shown in Fig. 6 and provided with perforations 12 to receive stitches; the tangs 9 and 11 being adapted 65 to engage the opposite sides of the slipper edge.

The separable plate is indicated at 13 and is here shown as comprising a substantially rectangular plate adapted to have its vertical edges slidably engaged by the inturned flanges 8 on the back plate. This separable plate is designed to be attached to a buckle, and for this purpose is formed with a series of perforations 14 on opposite sides of its 70 vertical center and adjacent to each end thereof; a pair of perforations being preferably provided on each side of the plate near one end thereof and several perforations provided on each side adjacent to the 75 other end thereof; these perforations 14 afford means whereby a buckle, ribbon or the like may be stitched to the separable plate. As a means for adapting the separable plate for attachment to a buckle 15 having a cross 80 bar 16 as shown in Fig. 4, the separable plate is formed with a longitudinally extending channel 17 on its back adapted to receive the back bar 16; the separable plate being disposed between the back bar and the 85 face of the buckle to effect engagement therewith.

As a means for retaining the separable plate against displacement on the back plate a pair of indents are formed from the back 90 of the back plate to provide projections 18 on the front face thereof in such position as to engage opposed perforations 14 in the separable plate. The perforations 14 being arranged in rows permit the separable plate 100 being disposed in various positions on the back plate with the projections 18 engaging either of the opposed pairs of perforations 14, thus providing an adjustment to adapt the device for use with buckles of various 105 sizes.

In attaching the back plate to the marginal edge of the slipper the tangs 9 are arranged to extend a short distance over the outer face of the slipper and are secured 110 thereto by stitching. As a means of affording a lock stitch, notches 19 are formed on

the edge of the tangs 9 opposite the openings 10 in which the threads extend in passing over the edge portion of the tangs. By passing the thread from opening to opening in each tang and thence over the edge thereof to engage the notches 19, a secure connection is effected between the back plate and the slipper so as to retain the back plate against movement relative to the point of its 10 connection with the slipper. If the third tang 11 is employed to project beneath the edge of the slipper, this tang will likewise be stitched to the slipper edge.

By attaching the back plate to the marginal edge of the slipper in the manner just described, objectionable projections beneath the vamp is obviated, which is important in that such projections afford discomfort and are apt to wear the stocking; the tangs 20 merely projecting beyond the edge of the slipper such distance as to enable stitching thereto.

In the application of the invention after the back plate is secured in place the separable plate is disposed in front of the buckle cross-bar with the latter extending in the longitudinal channel 17, or, if a buckle is used not having a cross-bar, or in event of a ribbon or the like being employed, such 25 buckle or ribbon is stitched to the separable plate as before mentioned. This separable plate may then be inserted lengthwise between the flanges 8 projecting forwardly from the outer face of the back plate and 30 moved downwardly between the flanges such distance as to dispose the lower edge of the buckle or ribbon in the desired position relative to the upper edge of the slipper. If the 35 projections 18 are employed these projections will engage the openings in the separable plate as before stated. As a means of affording various adjustments of the separable plate it is desirable that the spacing between the pair of openings 14 from the upper edge of the separable plate be different 40 from that of the openings adjacent to the lower edge of the separable plate so that, on inverting the separable plate and engaging a pair of openings with the projections 10, 45 the plate will be disposed in a position either higher or lower on the back plate than it would occupy if the opposite end were inserted in the back plate. As a means for concealing the support a filler 20 of any 50 suitable material is positioned between the separable plate and the back plate.

A modified form of the means for locking the separable plate on the back plate is shown in Fig. 7 which comprises a tang 21 55 formed on the upper edge of the back plate and adapted to be bent forward slightly to

project over the upper edge of the separable plate after the latter is put in place to hold it against accidental withdrawal.

When the separable plate is positioned on 65 the back plate and engaged by the said flanges the buckle will be securely held against accidental displacement and its proper position on the slipper insured.

While I have shown and described the 70 specific means for attaching the back plate to the slipper, it is obvious that any other suitable means of attachment may be employed if desired, and other changes may be made in the various details of construction 75 without departing from the spirit and scope of the invention as set forth in the accompanying claims.

I claim:

1. In a slipper buckle support, a back 80 plate, means for attaching said back plate to a slipper, a separable plate slidably engageable with said back plate having a longitudinal open-ended channel engageable with the back bar of a buckle, and means for temporarily retaining said separable plate 85 against slidable movement on said back plate.

2. In a slipper buckle support, a back 90 plate, inturned side flanges on the edges of said back plate, a pair of spaced tangs projecting from the lower edge of said plate adjacent to the lower ends of said flanges, said tangs adapted to seat on the edge of a slipper, a slidable plate detachably engageable 95 with said side flanges having a longitudinal open-ended channel extending to open to the space between the inner pair of tangs, and a buckle having a back bar adapted to be engaged between said slidable plate and back 100 plate to extend in the channel in the slidable plate and to project between the pair of tangs.

3. In a slipper buckle support, a back 105 plate, inturned side flanges on the edges of said back plate, a pair of spaced tangs projecting from the lower edge of said plate adjacent to the lower ends of said flanges, said tangs adapted to seat on the edge of a slipper, a slidable plate detachably engageable 110 with said side flanges having a longitudinal open-ended channel extending to open to the space between the inner pair of tangs, a buckle having a back bar adapted to be engaged between said slidable plate and back 115 plate to extend in the channel in the slidable plate and to project between the pair of tangs, and means for temporarily retaining said slidable plate against sliding movement on said back plate.

CHARLES F. COLBY.
